US00D628642S

(12) **United States Design Patent**
Tan

(10) **Patent No.:** **US D628,642 S**
(45) **Date of Patent:** **** Dec. 7, 2010**

(54) **PEN**

(75) Inventor: **Junlin Tan**, Ningbo (CN)

(73) Assignee: **Beifa Group Co., Ltd.**, Ningbo (CN)

(**) Term: **14 Years**

(21) Appl. No.: **29/353,095**

(22) Filed: **Dec. 31, 2009**

(30) **Foreign Application Priority Data**

Jul. 3, 2009 (CN) 2009 3 0189825

(51) **LOC (9) Cl.** **19-06**

(52) **U.S. Cl.** **D19/50**

(58) **Field of Classification Search** ..... D19/35, D19/36, 41, 42, 43, 44, 45, 46, 47, 48, 49, D19/50, 51, 54, 55, 56; D24/113, 114; D26/49; 24/11 F, 11 P, 11 R; 401/6, 52, 99, 100, 401/104, 105, 106, 107, 108, 109, 192, 195, 401/243, 244, 245, 246, 247; 708/107

See application file for complete search history.
